UNITED STATES PATENT OFFICE

LOUIS LICHTMAN, OF NEW YORK, N. Y., ASSIGNOR TO CHROMEPLATE, INC., OF NEW YORK, N. Y., A CORPORATION OF NEW JERSEY

HANGER FOR ARTICLES TO BE PLATED

Application filed November 27, 1928. Serial No. 322,221.

This invention is an improvement in hangers for articles to be plated, and more particularly in a hanger for chromium plating, enabling the articles to be supported in the most favorable position for receiving the deposit.

In electro-plating, the article is the cathode, and there must be a good electrical connection between the article and the hanger, with which the negative lead of the circuit is connected, in order to obtain a maximum of efficiency.

In certain ware, such as tubular articles, it is desirable that such articles be supported at both ends, and that the contact between the article and the hanger be relatively large, and at a plurality of points widely spaced.

One of the primary objects of the present invention is the provision of a type of hanger especially adapted for supporting tubular articles, wherein means is provided for engaging each end of the article to support the same in horizontal position.

Another object is to provide in such a hanger a supporting element which will contact with the article over a relatively large area and at points spaced widely from each other.

Another object is the provision in such a hanger of mechanism to enable easy removal and replacement of the article.

Another object is the provision of a simple and inexpensive construction adapted to support a maximum number of articles in a minimum of space.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:

Fig. 1 is a section of a plating tank provided with the improved hanger.

Fig. 2 is a section at right angles to Fig. 1.

Fig. 3 is a perspective view of one of the supports.

The present embodiment of the invention is shown in connection with a tank 1 of usual construction, provided with one or more conducting bars 2, arranged transversely of the tank, either crosswise or lengthwise, and a plurality of supporting bars 3 is suspended from the cross bar, it being understood that all of the parts previously described, and those to be described, are of conducting material.

Referring to Fig. 2, it will be noticed that the upper end of the bars 3 are offset laterally at their lower portions as shown at 4, and bent to engage the bar 2, the arrangement being such that the bars 3 will hang vertically. Two elements 3 are provided, the said elements being in the form of bars, depending from the cross bar 2. The positive electrodes 5 are supported in the tank in the usual manner, and the negative conductor is connected with all of the cross bars 2, when more than one is used.

Each of the elements 3 is provided at spaced 75 intervals on one face, with spring clips 6, in the present instance, connected by means of bolts 6^a. The clips are bent outwardly slightly from the bar 3 intermediate their ends, and their free ends engage the bar 3 80 closely.

The supporting elements are in the form of plates 7 relatively thick, and relatively long, and each has secured to one end thereof a rod 8, the end of the rod being flattened as 85 shown at 9 to fit the plate 7 closely, and the flattened end is riveted or welded to the plate.

In use, two of the supports are used, one in connection with each bar 3. The plates 8 are engaged beneath the clips 6, and the ends 90 of the rods extend into the ends of the tubular articles, one of said articles being indicated in dotted lines in Fig. 1. Thus, the article is supported at both ends, by a conductor which engages the article over a relatively 95 large area.

What is claimed as new is:

1. A hanger for tubular articles to be electro-plated, for engaging the interior of the article to leave the exterior fully exposed, in- 100

cluding rods for engaging within the ends of the article, hangers, and interengaging means in connection with the hangers and the rods for resiliently clamping the rods to the hangers.

5 2. In a hanger for tubular articles to be electro-plated, a pair of supporting bars, each having a hanger at its upper end, a plurality of spring clips secured to each bar, and rods

10 for engaging within the ends of the article, each rod having means to engage a clip to clamp the rod to the bar, the bars, clips and rods being of conducting material.

15 3. In a hanger for tubular articles to be electro-plated, a pair of supporting bars, each having a hanger at its upper end, a plurality of spring clips secured to one face of each bar, and rods for engaging within the ends of the article, each rod having means to engage a clip to clamp the rod to the bar, the bars, clips and rods being of conducting material.

20 4. In a hanger for tubular articles to be electro-plated, a pair of supporting bars each provided with a plurality of clips secured to one face thereof, rods for engaging within the ends of the articles, and plates to which the rods are connected for engaging beneath the clips.

25 30 Signed at New York city in the county of New York and State of New York this 5th day of November, A. D. 1928.

LOUIS LICHTMAN.
